SIMCHA YAFFE, NOW KNOWN AS SAM JAFFE, OF DETROIT, MICHIGAN.

MACHINE FOR BREAKING AND SOFTENING FEATHERS.

Application filed September 17, 1925. Serial No. 56,937.

This invention relates to means for reducing large and coarse flight feathers to short, pliable pieces which may serve as substitutes for the finer and softer feathers now employed for filling pillows and similar purposes, and it consists in a vertical cylindrical drum and an enclosing shell, both provided with closely spaced fingers for breaking the large coarse feathers into smaller pieces and for separating the fringe from the quill or stalk, means to feed the feathers to the upper end of the space between the shell and cylinder, and means to supply steam to this space to soften the feathers.

It further consists of any desired number of pairs of rolls adapted to receive the softened feathers and pieces from the breaking mechanism and to flatten the stalks and quills to render them pliable, and means to drive one roll of each pair at a faster surface speed than the other in order to produce the desired effect. It further consists of the details of construction illustrated in the accompanying drawings and particularly pointed out in the claims.

In the drawings, Fig. 1 is a diagrammatic view of an installation for softening feathers, embodying my invention. Fig. 2 is an elevation of the breaker. Fig. 3 is a section on the line 3—3 of Fig. 2. Fig. 4 is a perspective of a breaker pin. Fig. 5 is an elevation of several roll casings. Fig. 6 is a partial section of the cylindrical portion of the feather sorter. Fig. 7 is a detail thereof. Fig. 8 is a detail of the breaker and Fig. 9 is a section on the line 9—9 of Fig. 8. Fig. 10 is an end elevation of a set of rolls and Fig. 11 is vertical section thereof within the housing. Fig. 12 is a partial cross section of the breaker drum. Fig. 13 is a step bearing for the main shaft of the breaker drum.

Similar reference characters refer to like parts throughout the several views.

The coarser feathers of ducks and geese and nearly all chicken feathers are used to a very limited extent at the present time because they lack the softness and pliability demanded in feathers used as fillers of pillows and cushions. The heavy quills and stalks of these feathers render them very objectionable and practically useless for such purpose, but I have found that by breaking these coarse feathers and by separating the vane or fringe from the stalk as far as pos-

sible, and by flattening those pieces of stalk to which the fringe is still attached, I am able to produce a soft, springy material which approaches prime goose feathers in quality.

I have found that such a large portion of chicken feathers are benefited by the process carried out by my apparatus that it is not advisable to attempt to separate the fine feathers from the coarser. I prefer however to grade duck and geese feathers by means of an air blast which carries the lighter and finer down feathers along farthest from the blower and deposits the heavier feathers at lesser and diminishing distances so that it is an easy matter to gather up those considered too heavy for use in the raw state, these feathers being fed into my present apparatus to be broken and softened.

The device for grading feathers is indicated diagrammatically in Fig. 1, and consists of a housing 1 having feed chutes or hoppers 2 and 3. The discharge spouts 4 and 5 are provided with gates to determine the direction of discharge, the feathers to be graded being fed into the spout 3, carried along by the rapidly rotating cylinder 6, which turns counter clockwise in Fig. 1, and being discharged through the spout 4 with the blast of air produced by the cylinder. The teeth 7 on the cylinder pass through the notches 8 in the sides 9 of the spouts and serve to separate such feathers as may have become matted.

The cylinder 6 rotates at high speed when grading feathers, about 1200 R. P. M. being proper for an 18 inch cylinder. The feeding speed may be about 250 R. P. M.

The feathers to be softened are fed into the hopper 2 and the cylinder being rotated clockwise, are carried along the spout 5 to the breaker. Doors 4^a and 5^a control the blast in either direction.

The breaker consists of a vertical drum 10 mounted on a shaft 11 which may be supported by a step bearing of any desired type, the cup 12 and ball 13 being shown in Fig. 13. Any desired means may be employed to rotate this shaft, gears 14 and shaft 15 being shown. The drum is provided with a series of circumferential rows of pins or fingers 16, preferably semi-cylindrical, which pass between the circumferential rows of pins or fingers 17 extending inwardly from the shell 18. This shell is made of any desired number of sections and is provided with an up-

per head 19 which supports a hub 20 in which the shaft 11 is rotatable. If desired, another bearing 22 may be provided for this shaft.

5 The chute 5 connects to this upper head to discharge into the space between the drum and shell, and a pipe 23 is also connected into this head to conduct steam to the shell. The upper head 24 of the drum is provided 10 with holes (not shown) to permit the steam to enter the drum and the steam passes out through the holes 25 between the breaker pins (Fig. 8) to the feathers being broken by these pins. The stalks of the moistened 15 feathers are more easily broken and the fringe is more readily torn therefrom by the breaker pins than when the feathers are dry, probably because the moistened feathers adhere to these pins sufficiently to permit such 20 breaking and stripping. The stalks or quills are usually broken across. Only sufficient steam to dampen the feathers is admitted. The condensed steam drips down to the lower head 28 of the shell and is drawn off 25 through a pipe 27. The lower head 30 of the drum is formed with holes 70 to permit the water to escape, and is also formed with a flange 29 which nearly contacts with the inner wall of the shell and thus prevents the 30 feathers from falling to the lower head 28 of the shell.

A discharge spout 31 connects to the shell just above the flange 29 to conduct the feathers and parts thereof from the shell.

35 While any desired means may be employed to conduct the feathers to the pressing rolls, I prefer to employ an inclined conveyor comprising a belt 35 and cross slats 36 for the reason that it avoids the necessity of having 40 the bottom of the breaker above the rolls, which is often impossible on account of the lack of sufficient height of the rooms where this apparatus is to be used.

The conveyor 35 drops the feathers into 45 a hopper 37 just above a pair of presser rolls 38-39, which are driven in any desired manner, a belt pulley 40 being shown. I prefer to drive these rolls at different surface speeds so that the stalks of the feathers will 50 be disintegrated and the pith will be powdered. This can be accomplished by gearing the rolls together by means of the gears 42 and 43 of different sizes, and I prefer that the ratio of the gears shall be about 30 to 55 42. The pressure between the rolls can be regulated by the screws 41 which engage the bearings 44 for one of the shafts.

In order that the feathers will not stick 60 and pile up on the rolls I press a wiper 45 of rubber against each roll, the strip of rubber being mounted on a cross bar 46 carried in a guide groove 47 in the casing 48, and the pressure of the wiper on the roll may be adjusted by the screw 49, positioned central- 65 ly of the bar 46. Any other desired means

may be employed to support and adjust these wipers.

The feathers may pass from the first pair of rolls to a bin 51 through a chute 52 or may pass to a second set of rolls 53-54 70 through a chute 55, a door 56 being provided to determine the path. The second set of rolls may be identical with the first, but I prefer to have them adjusted somewhat closer so as to put a heavier pressure on the 75 feathers, which pass from these rolls to the bin 57 through a chute 58, or to the fan 59, a door 60 being provided to determine the path.

After the feathers in the form of fringe 80 and short lengths of stalks and quills leave the lower rolls and pass through the fan 59, they are blown out thereby and fall from the current of air, the short lengths of the quills and stalks falling together near the fan, the 85 heavier feather parts next thereafter and the finest parts farthest from the fan. This eliminates the hard and stiff portions and the small drops of fat that are found at the ends of the quills and attract insects or become rancid.

The details of construction may all be changed by those skilled in the art without departing from the spirit of my invention as set forth in the following claims. Thus 95 a second steam pipe 62 may be attached to the bottom 28 of the casing 18 should a larger amount of moisture be desired.

I claim:—

1. In a machine for breaking and flattening feathers, means to moisten the feathers and break them, a pair of rolls and means to convey the feathers from the breaker to the rolls, said rolls being driven at different surface speeds so as to disintegrate the stalks 100 of the feathers, a wiper contacting with each roll to prevent the feathers being carried around thereby, and means to adjust the wipers.

2. In a machine for breaking and flattening feathers, a vertical cylindrical casing 110 having rows of inwardly projecting pins, a vertical drum within the casing provided with outwardly projecting pins extending between the pins on the casing, means to rotate the drum, means to feed feathers to the upper end of the space between the drum and casing, means to convey the feathers from the lower end of such space, and means to conduct water vapor to the casing.

3. In a machine for breaking and flattening feathers, a vertical cylindrical casing having rows of inwardly projecting pins, a vertical drum within the casing provided 125 with outwardly projecting pins extending between the pins on the casing, means to rotate the drum, means to feed feathers to the upper end of the space between the drum and casing, means to convey the feathers from the lower end of such space, means to 130

conduct water vapor to the casing, and means to drain condensed water from the lower end of the casing, the lower head of the casing being bulged downward to collect such water.

4. In a machine for breaking and flattening feathers, a vertical cylindrical casing having rows of inwardly projecting pins, a vertical drum within the casing provided with outwardly projecting pins extending between the pins on the casing, means to rotate the drum, means to feed feathers to the upper end of the space between the drum and casing, means to convey the feathers from the lower end of such space, and means to then flatten and grind the feathers.

5. In a machine for breaking and flattening feathers, a cylindrical casing having rows of inwardly projecting pins, a cylindrical drum within the casing provided with rows of outwardly projecting pins alternating with the rows of pins in the casing, means to blow feathers into one end of the space between the drum and shell, means to moisten the feathers within such space, and means to rotate the drum.

6. In a machine for breaking and flattening feathers, a cylindrical casing having rows of inwardly projecting pins, a cylindrical drum within the casing provided with rows of outwardly projecting pins alternating with the rows of pins in the casing, means to blow feathers into one end of the space between the drum and shell, means to moisten the feathers within such space,

means to rotate the drum, a conveyor to receive the feathers from the opposite end of said space, and a pair of rolls to press the feathers.

7. In a machine for breaking and flattening feathers, a cylindrical casing having rows of inwardly projecting pins, a cylindrical drum within the casing provided with rows of outwardly projecting pins alternating with the rows of pins in the casing, means to blow feathers into one end of the space between the drum and shell, means to moisten the feathers within such space, means to rotate the drum, a conveyor to receive the feathers from the opposite end of said space, and a pair of rolls to press the feathers, said rolls being driven to have different surface speeds so as to disintegrate the stalks of the feathers.

8. In a machine for breaking and flattening feathers, a vertical cylindrical casing having rows of inwardly projecting pins, a vertical drum within the casing provided with outwardly projecting pins extending between the pins on the casing, means to rotate the drum, means to feed feathers to the upper end of the space between the drum and casing, and means to convey the feathers from the lower end of such space, said pins on the drum and casing being substantially semi-cylindrical with their faces in axial planes, those on the drum all facing in one direction and those on the casing facing in the opposite direction.

SIMCHA YAFFE.
